United States Patent Office.

JOHN R. ROSE AND EDWARD L. CALEY, OF PHILADELPHIA, ASSIGNEES TO THOMAS, ROBERTS, STEVENSON, AND COMPANY, OF BUCKS COUNTY, PENNSYLVANIA.

Design No. 8,193, dated September 1, 1868; antedated August 11, 1868.

DESIGN FOR COOK-STOVE PLATES.

The Schedule referred to in these Letters Patent and making part of the same.

TO ALL WHOM IT MAY CONCERN:

Be it known that we, JOHN R. ROSE and EDWARD L. CALEY, Jr., of the city of Philadelphia, in the State of Pennsylvania, have invented or produced a new and original Design for the Plates of a Cook's Stove; and we do hereby declare that the following is a full, clear, and exact description of the same, reference being had to the accompanying drawing, making a part of this specification, and to the letters of reference marked thereon.

In order to designate this stove from all others, we name it "The Times."

Our invention or production consists of the bas-relief ornamental figures a' b' c' d' on the raised panels of the respective plates A B C D, as shown in the drawing.

What we claim as our invention, and desire to secure by Letters Patent, is—

The design for the plates of a cook's stove, herein set forth and shown.

J. R. ROSE,
EDW. L. CALEY.
